UNITED STATES PATENT OFFICE.

FRANK CHATEAUNEUF, OF HAVERHILL, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,109,201.

Specification of Letters Patent.

Patented Sept. 1, 1914.

Application filed November 17, 1911. Serial No. 660,746.

To all whom it may concern:

Be it known that I, FRANK CHATEAUNEUF, a citizen of the United States, residing at Haverhill, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates to curved hook needle sewing machines of the class employed in sewing inseams of boots and shoes.

15 The objects of the present invention are to improve the construction and mode of operation of curved hook needle inseam sewing machines and to provide a sewing machine of this class by which an upper may 20 be attached to an unchanneled insole in a certain and satisfactory manner.

In accordance with the above objects the machine is provided with a sole engaging member or presser foot and with an awl 25 mounted to reciprocate in the direction of the line of feed and also to move into and out of engagement with the sole.

One feature of the invention contemplates arranging the awl to move through a perforation in the sole engaging member into and out of engagement with the sole. By reason 30 of this arrangement of the awl with relation to the sole engaging member the shoe can be turned and manipulated with greater facility particularly in sewing about curved portions of the sole such as the toe.

40 A further feature of the invention contemplates the provision of mechanism for operating the awl to maintain the same in engagement with the sole during the work piercing stroke of the needle, whereby lateral displacement of the sole due to the thrust of the needle is prevented. The sole engaging member is arranged to engage the 45 outer face of the sole and preferably to operate in the angle between the lip of the insole and the adjacent portion of the body of the insole to assist in guiding the shoe.

In the best form of the invention which has 50 yet been devised the sole engaging member is provided with a relatively broad, substantially flat surface arranged substan-

tially parallel with the plane of the insole for engagement with the outer surface of the insole, and with a face arranged to engage the inner side of the lip of the insole to form a guide for the shoe.

55 Further features of the invention consist of certain constructions, arrangements and combinations of parts, the advantages of 60 which will be obvious to one skilled in the art from the following description.

In the drawing illustrating the invention in its preferred form, Figure 1 is a side elevation partly in section of a portion of a 65 sewing machine embodying the invention. Fig. 2 is a front elevation of the mechanism illustrated in Fig. 1. Fig. 3 is a detail side elevation of the sole engaging member, the awl and portions of the levers by 70 which they are supported looking from the right hand side of the machine and showing the relative positions of the sole engaging member and awl when the awl is in engagement with the sole. Fig. 4 is a detail side 75 elevation of the mechanism shown in Fig. 3 illustrating the awl and sole engaging member in the relative positions which they assume when the awl is out of engagement with the sole. Fig. 5 is an under side plan 80 view of the sole engaging member detached.

The invention as illustrated is applied to a chain stitch curved hook needle shoe sewing machine of the well known Goodyear type and as such machines are well known 85 to those skilled in the art, only so much thereof is shown as is necessary for an understanding of the invention.

The sole engaging member for engaging the surface of the sole to assist in guiding 90 the shoe and holding the same in proper position with relation to the stitch forming mechanism during the sewing operation is indicated at 2. This sole engaging member is provided with a broad base or foot 3 for 95 engagement with the face of the sole and is preferably arranged so that the rear side of the base or foot engages the inner face of the lip formed on the outer portion of the sole during the sewing operation to assist in guiding the sole and in holding the same in proper position with relation to the stitch forming mechanism and so that the needle 1 operates close to the forward edge 100.

of the base. The lower or sole engaging surface of the base 3 is preferably roughened to enable the said member better to hold the sole.

The sole engaging member is preferably arranged to reciprocate in the direction of the line of feed and also to move into and out of engagement with the sole. The said member is held in engagement with the sole during the work piercing stroke of the needle, is lifted from engagement with the sole during its retreating movement while the thread is being laid in the hook of the needle, is again lowered into engagement with the sole as the needle retracts from the work and is held in engagement therewith during its work feeding movement. In the construction illustrated the sole engaging member is attached by means of screws 4 to an oscillatory lever 5, pivoted to oscillate in a plane parallel with the plane of the needle upon a shaft 6 carried by the feed slide 7. The lever 5 is provided with an arm 8 extending upwardly to a point adjacent the periphery of a cam disk 9 mounted on the main shaft of the machine.

A cam roll 10 is mounted on the end of the arm 8 and is arranged to engage a peripheral cam 11 formed on the cam disk 9, the cam roll being held in engagement with said cam by springs 12 hereinafter described. The said cam imparts through the cam roll 10 an oscillatory movement to the lever 5 and thereby to the sole engaging member 2. The cam is formed and arranged so that the sole engaging member is moved into and out of engagement with the sole in timed relation with the movements of the feed slide and the parts of the stitch forming mechanism. The feed slide is of the usual construction being provided with a rib or tenon 13 received in a suitable groove in the frame of the machine so that the feed slide is permitted to slide transversely in the direction of the line of feed. The feed slide is operated in the usual manner by a lever 15 pivoted at 16 and connected with said slide by means of a bolt or pin 17 secured to said lever and operating in a slot 18 in a bracket attached to said slide. The lever 15 is oscillated to impart the desired movements to the feed slide by means of a cam groove 19 formed in a cam disk attached to the main shaft of the machine in which cam groove a cam roll 20 attached to said lever operates. The movements thus imparted to the feed slide are substantially the same as in the ordinary Goodyear machine of this type.

The awl or feed point indicated at 21 is arranged to reciprocate in the direction of the line of feed with the sole engaging member and is also arranged to move independently of the sole engaging member into and out of engagement with the sole. The awl

in the present embodiment of the invention is held in engagement with the sole during the work piercing stroke of the needle, is lifted out of engagement with the sole during its retreating movement while the needle is in the work and the thread is being laid in the barb thereof, is again moved into engagement with the sole as the needle retracts from the work and is held in engagement therewith during its work feeding movement. By maintaining the awl in engagement with the sole during the work piercing stroke of the needle, the sole is held more securely from lateral displacement due to the thrust of the needle.

In order that the shoe may be manipulated with greater facility during the sewing operation, particularly in sewing about curved portions of the sole such as the toe, the awl is arranged to operate in a perforation in the sole engaging member. In the illustrated embodiment of the invention the awl is mounted in a block 22 secured to an operating lever 23 by means of a screw 24. The operating lever 23 is pivotally mounted to oscillate in a plane parallel with the plane of the needle upon a shaft 24^a carried by the feed slide and arranged beyond the shaft 6 so that the axis of the lever 5 is between the axis of the lever 23 and the sole engaging portions of the awl and the sole engaging member.

The operating lever 23 is provided with an arm 25 extending upwardly alongside the arm 8 of the lever 5 and the said arm 25 of the lever 23 is connected with the arm 8 of the lever 5 by means of a link 26. The link 26 is adjustably connected with the arm 25 of the lever 23 by means of a bolt 27 passed through a perforation in the said link and through a slot 28 in the arm 25 of said lever, thereby providing for the adjustment of the connecting point of the link with the lever toward and from the axis of the lever to vary the amplitude of movement of the awl. The springs 12 which act to hold the cam roll 10 in engagement with the cam 11 are each connected at one extremity to the upper arm of the lever 23 and at the other to the feed slide, as shown in Fig. 2.

In the mechanism above described when the lever 5 is oscillated to move the sole engaging member into and out of engagement with the sole, oscillatory movements are also imparted to the lever 23 through the connection of the said lever with the lever 5. Since the axis of the lever 23 is arranged beyond the axis of the lever 5 so that the axis of the lever 5 is between the axis of the lever 23 and the sole engaging portions of the awl and the sole engaging member, the amplitude of oscillation of the extremity of the awl will be greater than that of the sole

engaging portion of the sole engaging member. For this reason when the lever 5 is moved about its axis to lift the sole engaging member from engagement with the sole, 5 the awl is withdrawn from engagement with the sole within the perforation in the sole engaging member so that it cannot engage the sole during its retreating movement with the feed slide. When the lever 5 is operated 10 to bring the sole engaging member into engagement with the sole, the awl is projected beyond the sole engaging surface of the said member so that it projects a short distance into the substance of the sole when the sole 15 is in engagement with the sole engaging member as illustrated in Fig. 1. When the awl is in this position the shoe is firmly held against lateral displacement thereby.

The block 22 which constitutes the intermediate connection between the awl and the operating lever 23 is permitted a limited oscillatory movement with relation to the said operating lever upon the screw 24, thereby permitting the awl to accommodate itself 25 to the perforation in the sole engaging member during the relative movements of the sole engaging member and the awl.

The relative positions of the needle, the sole engaging member and the awl are illustrated in Figs. 1 and 2. As shown in Fig. 2 30 the needle operates in proximity to the left-hand edge or face of the foot of the sole engaging member when the said member has advanced to feed the shoe, and the awl is arranged out of alignment with the needle and therefore may be held in engagement 35 with the sole during the work piercing stroke of the needle without interfering with the operation of the needle.

40 **I claim—**

1. An inseam sewing machine having, in combination stitch forming mechanism including a curved hook needle arranged to enter and emerge from the outer face of 45 the sole during its work piercing stroke, a feed slide, a presser foot for engagement with the outer face of the sole supported on the feed slide for movement therewith and mounted for oscillatory movement to 50 engage and disengage the sole and having a perforation formed in the work engaging portion thereof, an awl supported on the feed slide for movement therewith and mounted for oscillatory movement through 55 the perforation in the sole engaging member to engage and disengage the sole, means to operate the feed slide and means to actuate the awl and sole engaging member.

2. An inseam sewing machine having, in 60 combination, stitch forming mechanism including a curved hook needle, a feed slide, a presser foot supported on the feed slide for

movement therewith and mounted for oscillatory movement to engage and disengage the sole and having a perforation formed in 65 the work engaging portion thereof, an awl supported on the feed slide for movement therewith and mounted for oscillatory movement through the perforation in the presser foot to engage and disengage the sole, means 70 to operate the feed slide, means to oscillate the presser foot and connections between the presser foot and awl for imparting oscillatory movements to the awl.

3. An inseam sewing machine having, in 75 combination, stitch forming mechanism including a curved hook needle, a feed slide, an oscillatory lever mounted on the feed slide, an awl carried by said lever, a second lever mounted on the feed slide to oscillate 80 on an axis parallel to the axis of said first lever and located between the axis of said first lever and the awl, a presser foot mounted on said second lever having a perforation formed in the work engaging portion 85 thereof in which the awl is arranged to operate, a link connecting the outer extremities of said levers and means to oscillate said second lever.

4. A sewing machine having, in combination, stitch forming mechanism including a curved hook needle, a feed slide, an oscillatory lever mounted on the feed slide, a presser foot mounted on said lever, a second lever mounted on the feed slide to oscillate 95 on an axis parallel with the axis of the first lever, an awl carried by the second lever, a link connecting the outer extremities of said levers and means to oscillate the first lever.

5. A sewing machine having, in combination, stitch forming mechanism including a curved hook needle, a feed slide, an oscillatory lever mounted on the feed slide, an awl carried by said lever, a second lever 105 mounted on the feed slide to oscillate upon an axis parallel with the axis of the first lever and located between the axis of the first lever and the awl, a presser foot mounted on the second lever, a link connecting 110 the outer extremities of said levers and means to oscillate the second lever.

6. A sewing machine having, in combination, stitch forming mechanism including a curved hook needle, a feed slide, an oscillatory lever mounted on said feed slide, an awl carried by said lever a second lever mounted on the feed slide to oscillate on an axis parallel with the axis of the first lever, a presser foot mounted on the second lever, 115 a link connecting the outer extremities of said levers, the first lever having provision for adjustment to locate the point of connection of the link therewith at different 120

distances from the axis thereof to vary the amplitude of movement of the awl.

7. An inseam sewing machine having, in combination, stitch forming mechanism including a curved hook needle, a feed slide, an oscillatory lever mounted on the feed slide, a presser foot having a perforation formed in the work engaging portion thereof secured to said lever, a second lever mounted on the feed slide to oscillate on an axis parallel with the axis of the first lever, an awl supported by the second lever and arranged to operate in the perforation in the presser foot, connections between the first lever and the awl permitting independent movement of the awl with relation to the first lever, a link connecting the outer extremities of said levers and means to oscillate the first lever.
8. An inseam sewing machine having, in combination, stitch forming mechanism including a curved hook needle arranged to enter and emerge from the outer face of the sole during its work piercing stroke, a sole engaging member for engagement with the outer face of the sole mounted to reciprocate in the direction of the line of feed and having a perforation formed in the work engaging portion thereof, an awl arranged to reciprocate with the sole engaging member in the direction of the line of feed and also arranged to move through the perforation in the sole engaging member into and out of engagement with the sole, means to reciprocate the sole engaging member and the awl in the direction of the line of feed and means to move the awl into and out of engagement with the sole.

9. An inseam sewing machine, having, in combination, stitch forming devices including a curved hook needle arranged to enter and emerge from the outer face of the sole during its work piercing stroke, a sole engaging member arranged to engage the outer face of the sole and having an opening formed in the work engaging portion thereof, an awl arranged to move through the opening in the sole engaging member into and out of engagement with the work, and means to actuate the awl.

10. An inseam sewing machine, having, in combination, stitch forming devices including a curved hook needle, a sole engaging member having an opening formed in the sole engaging portion thereof, an awl arranged to move through the opening in the sole engaging member into and out of engagement with the work, and means to actuate the awl constructed and arranged to maintain the awl in engagement with the work during the work piercing stroke of the needle.

11. An inseam sewing machine, having, in

combination, stitch forming devices including a curved hook needle arranged to enter and emerge from the outer face of the sole during its work piercing stroke, a sole engaging member arranged to engage the outer face of the sole and having an opening formed in the work engaging portion thereof, an awl arranged to move through the opening in the sole engaging member into and out of engagement with the work, and means to actuate the awl constructed and arranged to maintain the awl in engagement with the work during the work piercing stroke of the needle. 65

12. An inseam sewing machine, having, in combination, stitch forming devices including a curved hook needle arranged to enter and emerge from the outer face of the sole during its work piercing stroke, a sole engaging member for engagement with the outer face of the sole in the angle between the lip thereof and the adjacent portion of the body of the sole having an opening formed in the work engaging portion thereof, an awl arranged to move through the opening in the sole engaging member into and out of engagement with the work, and means to actuate the awl. 70 80

13. An inseam sewing machine, having, in combination, stitch forming devices including a curved hook needle arranged to enter and emerge from the outer face of the sole during its work piercing stroke, and a sole engaging member provided with a relatively broad, substantially flat surface arranged parallel with the plane of the sole for engagement with the outer face of the sole 95 and with a face for engagement with the inner face of the lip of the insole to form a guide for the shoe. 100

14. An inseam sewing machine, having, in combination, stitch forming devices including a curved hook needle arranged to enter and emerge from the outer face of the sole during its work piercing stroke, and a sole engaging member provided with a relatively broad, substantially flat surface arranged parallel with the plane of the sole for engagement with the outer face of the sole and with a face for engagement with the inner face of the lip of the insole to form a guide for the shoe, said member having an opening formed in the work engaging portion thereof, an awl arranged to move through the opening in the sole engaging member into and out of engagement with the work, and means to actuate the awl. 110 115

15. An inseam sewing machine, having, in combination, stitch forming devices including a curved hook needle arranged to enter and emerge from the outer face of the sole during its work piercing stroke, a sole engaging member arranged to engage the

outer face of the sole and having an opening formed in the work engaging portion thereof, an awl arranged to move through the opening in the sole engaging member into and out of engagement with the work, and means for moving the sole engaging member into and out of engagement with the sole and for simultaneously projecting

the awl through and withdrawing the awl within the opening in the sole engaging member.
